BETHEL ABIEL REVELLI, OF TURIN, ITALY

FOUR-BARRELED PISTOL

Application filed April 22, 1929, Serial No. 357,220, and in Italy April 25, 1928.

This invention has for its object a four barreled pistol having a single striker which is brought by rotation to register in succession with each of the barrels. The axes of 5 the four barrels pass through the four vertices of a quadrangle, the intersection points of the diagonals of said quadrangle being also the center of rotation of the striker. The striker is eccentrically mounted on the hammer, which is constituted by a small cylinder 10 revolvably mounted on its axis on the end of an oscillating lever actuated by the trigger. When the hammer is brought into the cocked position, the small cylinder carrying the 15 striker performs the fourth part of a revolution on its axis. At the end of its stroke the lever is released under the action of a spring and the striker hits the cap of one of the four cartridges causing the firing. The arrangement 20 producing the rotation of the small cylinder and striker is constituted by a ratchet and pawl mechanism, the four teeth of which are arranged on the cylinder end opposed to the end carrying the striker, while 25 the pawl follows the lever during its oscillation and by its oscillation on another pin causes the cylinder to advance by one tooth.

The cocking releasing and percussion mechanism is carried by a frame forming 30 also the arm stock, to which is secured the barrel block revolving on an eccentric pin, namely outside the quadrangle enclosing the barrel bores, so that introduction of the cartridges and extraction of the fired cartridge 35 cases will be possible.

Normally and particularly during firing, the barrel block is maintained in place by suitable groove and tongue joints forming a shoulder and by a closure device the opening 40 of which brings the striker out of operation. The loading is effected by inserting the cartridges individually (except when a simultaneous loading device, easy to be constructed but of little use for the purpose of 45 this invention, is used), while the four fired cartridge cases are extracted simultaneously by means of a star-shaped extractor having a pin passing longitudinally through the axis of the barrel block from which it 50 protrudes in such a way as to be pressed directly

or indirectly against the action of a barrel spring.

The annexed drawing shows by way of example the pistol forming the object of this invention, its stock elements having been removed in order to make its inner members 55 visible.

Fig. 1 is a front view of the arm.

Fig. 2 is a side view thereof.

Fig. 3 is a longitudinal section of the arm 60 through its middle plane when ready for firing.

Fig. 4 is a front view of the mechanism causing the rotation of the cylinder and 65 striker, the stock being sectioned at its rear part.

Figs. 5 and 6 show in two different positions the closure mechanism of the barrel block acting also as safeguard during loading 70 and extraction.

The arm frame is in the form of a stock and consists of a case closed at its rear end by a wall 1 and at its front end by the trigger guard. The upper wall of said case comprises a higher rear portion 3 carrying a pin 20 on which the barrel block 18 oscillates and a lower cradle-shaped front portion 4 receiving the barrel block and provided with grooves in which engage ribs of said block and an intermediate vertical portion 5 provided with four holes 5' through which the 75 striker passes during operation.

The lower part of said case comprises a portion 6, a guard 2 and an intermediate portion 7 provided with ears 7', in which is fitted the pin on which the lever 8 carrying the hammer oscillates.

The rear wall 1 is provided with ears 1' carrying the pin of the lever 9 on which the pawl producing the rotation of the hammer 80 cylinder is mounted. Said cylinder 10 is revolvably mounted on the end of the lever 8 and carries on one side a flange 11 with an eccentric striker 12 and on the other side a ring 13 secured thereon by a screw and having four teeth 14 with inclined faces. The lever 9 carries at its end (Fig. 4) a spring pawl 15, which—oscillating from the position shown in Fig. 2 to the position shown 85 in Fig. 3—comes into contact with the teeth 100

14 causing the cylinder 10 to perform the fourth part of a revolution, said lever being inoperative during the return oscillation. The levers 8 and 9 are connected kinetically by means of a slot 8' and pin 16 provided in one of said levers and a slot 9' provided in the other lever and in which passes the said pin. The lever 8 is provided at its lower end with a helical spring 17 holding it from back oscillation and forcing it forward for the percussion.

The barrel block 18 has four bores 19, the axes of which (Fig. 1) pass through the vertices of a quadrangle, the wall 5 being provided with funnel shaped holes 5' registering with said barrel bores and through which the striker 15 successively passes at each full oscillation of the lever 8. The barrel block 18 is held in contact with the stock by means of a pin 20 secured to the wall 3 by a plug, the barrel block revolving on said pin. During firing the pressure is transmitted to the cradle 4 of the stock through the grooves 4' and 4'', in which engage the ribs 18' and 18''. The normal position of the block 18 in the cradle 4 is ensured by a latch, as it will be hereafter described.

The block 18 is rotated through one half revolution, as shown in dotted lines in Fig. 2, for the purpose of effecting the loading of the barrel and the extraction of the fired cartridge cases. This operation may be effected by means of a star-shaped extractor 21 operated by means of a rod 22 mounted in a longitudinal opening of the barrel block and slightly protruding from the front end of said block. By pressing said rod, the extractor is brought out with the cartridge cases; a spring 23 returns the rod 22 into its rest position as soon as the pressure on the rod is released.

The cocking and firing are effected by pressing on the trigger 24 pivoted on the cradle 4. Said trigger is substantially constituted by a plate having a deep groove, in which are pivotally mounted the levers 25 and 26, this latter acting as a sear.

The two springs 25' and 26' tend, the former to return the trigger into its rest position forcing the lever 25 against the cradle 4, the second to cause the lever 26 to slide against the lever 8 causing it to oscillate until it enters the slot 8', at which time the lever 8 is released and causes the striker to hit one of the four cartridges. The trigger when released returns to its rest position and is ready for a new shot.

Figs. 5 and 6 show the closure device of the block 18. The rib 18'' of this latter is provided with a longitudinal cut in which engages a tooth 27' of a lever 27 pivotally mounted in the stock, an extension 27'' of the lever 27 abuts against the lever 8. By causing the lever 27 to oscillate from the position of Fig. 5 to the position of Fig. 6, the

rib 18'' is disengaged from the tooth 27' and at the same time the lever 8—and consequently the striker—is removed from the barrels, not only setting these latter free, but preventing hitting, through an accidental release during handling, a cartridge not yet fired. Said lever 27 may be so formed as to act as a safety device.

The characteristic devices above described may of course be used in connection with any firearm other than a pistol without departing from the scope of this invention.

What I claim is:

1. Four barreled pistol comprising in combination with a frame and a barrel block having four bores situated at the vertices of a quadrangle, of a hammer constituted by a percussion lever mounted capable of oscillating in the frame, a cylinder revolvably mounted on one end of said lever, a striker eccentrically secured on said cylinder, a ring secured to the cylinder and carrying four ratchet teeth, a second lever pivotally mounted in the frame and connected by means of a groove and tongue joint to said percussion lever and carrying a pawl cooperating with said teeth in such a way as to cause the cylinder to advance by one tooth at each back oscillation of said percussion lever, a spring tending to cause said percussion lever to effect its percussion movement and a trigger forcing said percussion lever backwards, said trigger becoming disengaged from the percussion lever at the end of its operative stroke.

2. Four barreled pistol comprising in combination a frame, a barrel block having four bores situated at the vertices of a quadrangle and mounted capable of oscillating on an eccentric pin, said eccentric pin being secured to the frame parallel to the barrel and engaging in an opening of the barrel block situated outside the circle passing through the bore axes, a cradle in the frame supporting said barrel block, means for fastening the barrel block to the cradle, a hammer constituted by a percusion lever mounted capable of oscillating in the frame, a cylinder revolvably mounted on one end of said lever, a striker eccentrically secured to said cylinder, a ring secured to the cylinder and carrying four ratchet teeth, a second lever pivotally mounted in the frame and connected by means of a groove and tongue joint to said percusion lever and carrying a pawl cooperating with said teeth in such a way that the cylinder is caused to advance one tooth at each back oscillation of said percusion lever, a spring tending to cause said percusion lever to effect its percusion movement and a trigger forcing said percusion lever backwards, said trigger becoming disengaged from the percusion lever at the end of its operating stroke.

3. Four barreled pistol comprising in combination a frame, a barrel block having four

bores situated at the vertices of a quadrangle and mounted capable of oscillating on an eccentric pin, said eccentric pin being secured to the frame parallel to the barrels and engaging in an opening of the barrel block situated outside the circle passing through the bore axis, a cradle in the frame supporting said barrel block, means fastening the barrel block to the cradle, a hammer constituted by 5
10 a percussion lever mounted capable of oscillating in the arm frame, a cylinder revolvably mounted on one end of said lever, a striker eccentrically secured on said cylinder, a ratchet and pawl mechanism to cause said cylinder to perform the fourth part of a revolution at each oscillation of said lever, a trigger operating said lever and means for 15 bringing said percussion lever into the safety position when the barrel block is disengaged 20 from the locking means.

4. Four barreled pistol comprising in combination a frame, a barrel block having four bores situated at the vertices of a quadrangle, a star-shaped extractor, a rod operating 25 said extractor slidably mounted in a central opening, a hammer constituted by a percussion lever mounted capable of oscillating in the frame, a cylinder revolvably mounted on one end of said lever, a striker eccentrically 30 secured on said cylinder, a ring secured to the cylinder and carrying four ratchet teeth, a second lever pivotally mounted in the frame and connected by means of a groove and tongue joint to said percussion lever and carrying a pawl cooperating with said teeth in 35 such a way as to cause the cylinder to advance one tooth at each back oscillation of said percussion lever, a spring tending to cause said percussion lever to effect its percussion movement and a trigger forcing said 40 percussion lever backwards, said trigger becoming disengaged from the percussion lever at the end of its operating stroke.

In testimony that I claim the foregoing as 45 my invention, I have signed my name.

BETHEL ABIEL REVELLI.
